UNITED STATES PATENT OFFICE

LERoy R. PIERCE, OF KEYSTONE, OKLAHOMA

WIRE LINE SHOCK ABSORBER

Application filed February 25, 1930. Serial No. 431,208.

This invention relates to oil and other well rigs and more particularly to an attachment for such rigs utilizing a wire line drilling cable in lieu of the usual manila drilling cable.

One of the primary objects of my invention is the provision of a novel shock absorber for the wire line drilling cable of a well rig, whereby a wire line can be successfully used with such rigs in lieu of the manila cable. In well drilling a certain necessary give is inherent in the ordinary manila cable, which is missing in the wire line cable and which prevents the effective use of such wire line cable on a drilling rig.

It is therefore, another prime object of my invention to provide a shock absorbing and tensioning device for engaging a wire line drilling cable carried directly by the well rig and arranged between the bull wheel or windlass and the derrick, said shock absorbing and tensioning device permitting the desired give to the wire line cable.

A further important object of my invention is the provision of novel means for constructing the shock absorbing and wire line tensioning device, whereby an efficient structure will be had which can be conveniently associated with an ordinary well rig for receiving the wire line cable at an intermediate portion thereof.

A still further object of my invention is to provide a wire line shock absorbing and tensioning device for well rigs of the above character, which will be durable and efficient in use, one that will be simple and easy to manufacture, and one which can be placed upon the market at a reasonable cost.

With these and other objects in view, the invention consists in the novel construction, arrangement and formation of parts, as will be hereinafter more specifically described, claimed, and illustrated in the accompanying drawing, in which drawing:

Figure 1 is a fragmentary side elevation of a well rig showing parts thereof broken away and in section with my improved device incorporated therewith, my device being shown in side elevation.

Figure 2 is a front elevation of my im-

proved device showing parts thereof in section.

Figure 3 is a vertical section through the same taken on the line 3-3 of Figure 2 looking in the direction of the arrows.

Figure 4 is a detail section taken on the line 4-4 of Fig. 2, looking in the direction of the arrows.

Referring to the drawing in detail, wherein similar reference characters designate corresponding parts throughout the several views, the letter A generally indicates my improved device and B a well rig with which the same can be associated.

The well rig B may be of any preferred or conventional character and includes the usual lower frame work 10, platform 11, and derrick 12. The lower frame work 10 includes an end transverse beam 13 arranged below the bull wheel 14 around which is coiled the wire line drilling cable 15. As shown, the wire line drilling cable 15 extends from the bull wheel 14 over a suitable guide roller or pulley 16 and then up and over the top of the derrick and the crown pulley carried thereby. In as much as the well rig B is of conventional construction further description thereof will not be given in this specification.

My improved line wire shock absorber and tensioning device for wire line cable 15 comprises a sheave or pulley wheel 20 rotatably mounted upon an axle or shaft 21 carried by the pulley frame or block 22 which may be formed of sheet metal. As shown, the pulley block or frame 22 is provided with an enlarged open base 23 having its inner lower end provided with an opening for the reception of the slide bolt 24, the head 25 of which engages the inner face of the base 23 of the pulley frame or block 22. One side of the frame is provided with a slot or opening 26 whereby the cable can be readily introduced into the block so that the same can engage around the pulley wheel or sheave 20. This slot 26 can be normally closed by the use of any preferred type of latch 27. The slide bolt 24 also slidably extends through a protecting plate 28 which is connected by means of lag screws 29 or the like to the transverse

beam 13 of the well rig frame 10 and the slide bolt slidably extends through an opening 30 formed in said beam.

The lower surface of the beam 13 has connected thereto by the use of lag screws 31 or the like an angle iron protecting strip 32 which strip at its central portion carries a hollow guide boss or collar 32 and adjacent to its opposite ends it carries the hollow 10 bosses or guide collars 33. As clearly shown in Figure 3 of the drawing, the slide bolt 24 extends through the central boss or collar 32 and through the central sleeve 35 of the tension frame 36. Threaded on the lower or 15 outer end of the slide bolt or strain rod 24 is a nut 37 which engages the outer lower face of the tension frame 36. The tension frame 36 on each side of the central sleeve 35 is provided with side sleeves 38 which slidably receive the side guide rods 39 which are secured to or formed on the guide bosses 33. The slide bolt or strain rod 24 and the guide rods 39 receive the compression springs 40 which are interposed between the tension 25 frame 36 and the bosses 32 and 33 and normally function to draw the frame 36 away from the beam 13 and consequently the sheave or pulley wheel 20 toward said beam.

As clearly shown in Figure 1 of the drawing, the sheave or pulley wheel 20 engages the wire line cable 15 and thus exerts a continuous tension thereon and any strain on the cable will be absorbed by the springs 40 and due to the construction of the device and the arrangement thereof on the frame the maximum amount of benefit will be derived from the resilient mounting of the pulley wheel and the engagement thereof with said wire line.

Changes in details may be made without departing from the spirit or the scope of this invention, but

What I claim as new is:

1. A shock absorbing device for use in connection with well rigs comprising an angle iron protecting strip adapted to fit over the under and outer side of a bracing beam of a rig, a slide bolt slidably mounted through said protecting strip and extending through said bracing beam at an angle of approximately forty-five degrees to the transverse axis of said bracing beam, a tension frame secured to the outer end of said slide bolt, a plurality of guide rods carried by said protecting strip and extending in parallel relation with respect to said slide bolt and slidably mounted through said tension frame, coil springs interposed between said tension frame and said protecting strip and mounted upon said slide bolt and guide rods for normally urging said tension frame outwardly with respect to said protecting strip, said guide rods constituting means for resisting lateral strain upon said slide bolt, and means carried by the inner end of said slide bolt

for engaging the wire line cable of a well rig.

2. A shock absorbing device particularly designed for use in connection with well rigs comprising an angle iron protecting strip adapted to fit over the under side of a bracing beam of a well rig, a guiding boss formed centrally of said protecting strip, a slide bolt slidably mounted through said boss and extending through said bracing beam at an angle of approximately forty-five degrees to the transverse axis of said bracing beam, a protecting plate mounted adjacent said protecting strip and in line with said boss for constituting a support for the inner end of said slide bolt, means carried by the inner end of said slide bolt for engaging the line wire of a well rig, an elongated tension frame secured to the outer end of said slide bolt, a spring mounted upon said slide bolt intermediate said boss and said tension frame, a plurality of sleeves formed upon said tension frame, guide rods slidably mounted through said sleeve and secured at their inner ends to said protecting strip, and springs mounted upon said guide rods for normally urging said tension frame outwardly with respect to said protecting strip, said guide rods assisting in resisting the lateral strain upon said slide bolt.

In testimony whereof I affix my signature. 95
